THE MORRIS PRESS COMPANY
WASHINGTON, D. C.

UNITED STATES PATENT OFFICE.

JOHN W. McDOWELL, OF ST. LOUIS, MISSOURI.

COMBINED WATER-BAG, SYRINGE, AND COLONIC IRRIGATOR.

No. 837,947.

Specification of Letters Patent.

Patented Dec. 11, 1906.

Application filed February 8, 1906. Serial No. 300,138.

To all whom it may concern:

Be it known that I, JOHN W. McDOWELL, a citizen of the United States, residing at St. Louis, in the State of Missouri, have invented 5 certain new and useful Improvements in a Combined Water-Bag, Syringe, and Colonic Irrigator, of which the following is a specification.

This invention relates to an improved 10 water - bag, fountain - syringe, and colonic irrigator, the irrigator being of the type in which the pressure for injecting the liquid is furnished by the weight of the patient's body.

15 In all prior devices of this type, so far as I am aware, great difficulty has been experienced in providing a regulating-valve which will prevent leakage through the moving parts when the irrigator is in use. This 20 difficulty is obviated by the construction shown in the drawings accompanying this specification, in which—

Figure 1 is a plan view of my device arranged as an irrigator. Fig. 2 is a longitudinal section showing a tube attachment for use as a fountain-syringe. Fig. 3 is an enlarged section of the base of the irrigator-nozzle. Fig. 4 is a section showing the application of the closing-cap. Fig. 5 is an 30 elevation of the device arranged as a fountain-syringe, and Figs. 6 to 9 are detail views hereinafter referred to.

1 is the rubber receptacle provided with side and end orifices 2, which when not required for use may be closed with caps 2', preferably made interchangeable.

3' are valved attachments, the former being arranged to receive a suitable length of flexible tubing 4 and the latter to receive a 40 nozzle 5, which nozzle may also be attached, as shown in Fig. 5.

6' are screw-plugs each larger in diameter than the orifice 2 which it is adapted to cross to practically close said orifice, as 15 clearly shown in Fig. 9, the ends of said plugs being preferably concaved and provided with disks or short cylinders 7, of rubber or the like, sufficiently flexible and resilient, especially at their forward or free ends, to be 20 partially straightened, and thus expanded, by hydraulic pressure acting on their free faces. The forward portion of the bore which receives the plugs 6' is without interior screw - threads, and the resilient 25 pieces 7 are preferably of sufficient length to

span the orifices 2 when moved thereover and seal them when the bag is being filled, &c.

In order that the disks may be attached to the tips of the plugs and renewed if necessary, the valve-casings are provided with suitably-located orifices 10, slightly larger than the threaded orifices through which the plugs pass, and the orifices 10 are also provided with rubber-lined caps 2''. The junction of the smooth and threaded portions of the interior of the valve-fittings opposite the caps 2'' forms a coned seat, as best shown in Fig. 9.

The operation of the device as a hot-water bag will be clearly apparent. All fittings are removed, and both orifices 2, one of 70 which may serve as a filling-orifice, are closed with the caps 2''. Its operation as a fountain-syringe will be apparent from Fig. 5. When used as a colonic irrigator, the fittings are arranged as shown in Fig. 1, the filled bag 75 placed on a seat of convenient height, the fluted nozzle given a rectal insertion, and the patient seats himself upon the reservoir with the valve-plug directed toward the front of the body. The flow of the fluid is then 80 readily regulated either by manipulation of the valve or by varying the weight upon the reservoir. When the valve is fully opened, as shown in Fig. 9, it will be readily understood that the greater the fluid-pressure upon 85 the yielding disk 7 the more secure the sealing of the valve against leakage. The same is true of the valve 6 when the device is used as a fountain-syringe.

What I claim is—

1. In a combined water-bag, syringe and irrigator, a compressible receptacle provided with a plurality of orifices each having a removable valve structure, and a sealing-cap interchangeable with said valve structures 95 for closing either of said orifices; substantially as described.

2. In a device of the class described, a regulating-valve comprising a casing having a straight orifice therethrough, and a closing-plug of greater diameter than the straight orifice and movable in a transverse passage across said orifice, said plug having a resilient tip constructed and arranged to seat against that end of the passage through which the 105 plug moves, to seal said transverse passage against leakage when the valve is fully opened; substantially as described.

3. In a device of the class described, a valve structure comprising a casing having 110

two straight, intersecting orifices of different diameters therethrough, a screw-plug movable longitudinally of the larger orifice and transversely of the smaller orifice, to close the latter, said plug having a resilient member at its inner end arranged to contact with a seat at that end of the orifice at which the plug enters to seal the larger orifice against leakage when the valve is fully opened; substantially as described.

4. In a device of the class described, a valve comprising a casing having a straight outlet-orifice therethrough and a transverse passage larger than the outlet-orifice, screw-threaded for a portion of its length and intersecting said orifice, said passage having a

coned seat adjacent to the screw-threaded portion, a screw-threaded plug fitting the threads of said transverse passage and movable across said outlet-orifice to close the same, said plug having a resilient member secured to its inner extremity and adapted to contact with said coned seat to prevent leakage around the screw-plug when the valve is in open position; substantially as described.

In testimony whereof I affix my signature in presence of two witnesses.

JOHN W. McDOWELL.
